US00D976437S

(12) **United States Design Patent** (10) **Patent No.:** **US D976,437 S**
(45) **Date of Patent:** **** Jan. 24, 2023**

(54) **COLLECTION DEVICE**

- (71) Applicant: **Becton, Dickinson and Company**, Franklin Lakes, NJ (US)
- (72) Inventors: **Weston F. Harding**, Lehi, UT (US); **Austin Jason McKinnon**, Herriman, UT (US); **Matthew Oshinski**, Oak Ridge, NJ (US)
- (73) Assignee: **Becton, Dickinson and Company**, Franklin Lakes, NJ (US)
- (**) Term: **15 Years**
- (21) Appl. No.: **29/795,837**
- (22) Filed: **Jun. 21, 2021**

(57) **CLAIM**

The ornamental design for a collection device, as shown and described.

DESCRIPTION

FIG. 1 is a top, left, and front perspective view of an embodiment of a collection device, showing our new design; FIG. 2 is a top, right, and front perspective view thereof; FIG. 3 is a front elevation view thereof; FIG. 4 is a back elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a bottom, left, and front perspective view thereof; and, FIG. 10 is a bottom, right, and front perspective view thereof. The broken lines illustrate portions of the collection device which form no part of the claimed design.

1 Claim, 8 Drawing Sheets

Related U.S. Application Data

division of application No. 29/618,544, filed on Sep. 21, 2017, now Pat. No. Des. 859,683.
